UNITED STATES PATENT OFFICE.

WILLIAM WALLACE, OF OAKLAND, CALIFORNIA.

DRESS-MAKER'S RULE.

SPECIFICATION forming part of Letters Patent No. 284,783, dated September 11, 1883.

Application filed July 9, 1881. (No model.)

To all whom it may concern:

Be it known that I, WILLIAM WALLACE, a citizen of the United States, and residing at 5 Oakland, in the county of Alameda and State of California, have invented a new and useful Dress-Maker's Rule, of which the following is a specification.

The object of my invention is to provide a dress-maker's rule having the necessary lines, 10 figures, and curves that will enable the operator not only to draw accurate lines, but also to draft any curve requisite in dressmaking.

Figure 1 represents my improved rule on a reduced scale, showing its general form; and 15 Fig. 2 is a plan of same, enlarged and broken to economize space, the various lines, measures, and characters with which the rule is provided being shown complete and in their proper positions.

20 A represents the long arm of this rule, which is eighteen inches in length, and B the short arm, three and one-half inches in length; D, the upper front neck; E, the lower front neck; F, the back of neck; G, the size of breast; H, 25 size of back; I, front armhole; J, size of front armhole; K, size of back armhole; S, curvature for sleeve-head. Curvature No. 1 is a forming-rule; curvature No. 2, a neck-curve. No. 1' represents the corner of rule, and No. 30 2' corner opposite No. 1' at the other end of the rule, and Fig. 3' point at the junction of the curvature of Nos. 1 and 2 of the rule. The darts or arrows are designated by 1" and 2".

4' is the back-waist line. 5' is a star used in drafting collars, and 6' size of back neck for 35 collars.

The proportions of the measures of the different parts of the form are printed or marked on the rule, as shown, so that any form from the smallest to the largest can be readily 40 drafted without entering into a tedious calculation. By the use of this rule the exact dart required can be given to each form, thus obviating the difficulties arising from an incorrect dart. The proper pitch of the shoulder 45 can also be readily obtained, thus avoiding any necessity of making alterations on the shoulder and in the armhole.

Having thus described my invention, what I claim as new, and desire to secure by Letters 50 Patent, is—

The herein-described dress-maker's rule, having the long arm or side, A, short arm or side, B, and the curvatures No. 1 and No. 2, said arms and curvatures being marked with 55 the various scales for showing the proportionate measures of the different parts of the form, substantially as specified.

In testimony that I claim the foregoing I have hereunto set my hand and seal this 27th 60 day of June, 1881.

WILLIAM WALLACE. [L. S.]
